CLAIM

The ornamental design for a fan light, as shown and described.

DESCRIPTION

FIG. 1 is a front perspective view of a fan light showing my new design.

FIG. 2 is a rear perspective view of a fan light.

FIG. 3 is a front view of a fan light.

FIG. 4 is a rear view of a fan light.

FIG. 5 is a left side view of a fan light.

FIG. 6 is a right side view of a fan light.

FIG. 7 is a top view of a fan light; and,

FIG. 8 is a bottom view of a fan light.

Any shading and cross-hatching are not features of the design but are utilized to illustrate the surface contours of the fan light design in the drawings.

The dashed broken lines depict portions of the fan light that form no part of the claimed design.

1 Claim, 8 Drawing Sheets
